UNITED STATES PATENT OFFICE.

HORATIO ANDERSON, OF CHICAGO, ILLINOIS, ASSIGNOR TO HIMSELF AND
GEO. W. CUSHING, OF SAME PLACE.

IMPROVEMENT IN STEAM-GENERATOR SAFETY-VALVES.

Specification forming part of Letters Patent No. **58,934**, dated October 16, 1866.

To all whom it may concern:

Be it known that I, **HORATIO ANDERSON**, of Chicago, county of Cook, and State of Illinois, have invented a new and useful Improvement in Safety-Valves; and I do hereby declare that the following is a full, clear, and exact description thereof, which will enable others skilled in the art to make and use the same, reference being had to the accompanying drawings, forming part of this specification, in which—

Figure 1 is an inverted plan of the valve; Fig. 2, a partial section of the valve and connected parts thereof; Fig. 3, an inside view of flange for containing valve-seat and attaching to boiler.

Similar letters of reference indicate like parts.

This invention is designed to furnish a safety-valve to be attached to locomotive, marine, or stationary boilers for preventing explosions by an excessive pressure of steam. It is adjustable to whatever pressure is deemed safe, and is secured to the inside of the dome or boiler in such manner that it cannot be altered or tampered with by an engineer or any other person, and will always act promptly in discharging an excess of steam, if it should rise above the point of safety.

A is a flange to be bolted and packed steam-tight upon the dome or shell of a boiler, in the center of which is fitted the valve-seat **a**. **b** is a stand or bearing on the inside of the flange **A**, which supports the capsular spring **c**, and through which passes the valve-stem **d**. **B** is

the valve—a circular plate or beveled disk fitted to the seat **a** upon the outside of the flange **A**.

The stem **d** screws into the hub **e** of the valve **B**, and on the hub or boss **e** are guides **f f f** in the valve-seat **a**. Around the stem **d** and supported on the stand **b** is wound the capsular spring **c**, which is secured to the stem by the washer **g** and the jam-nuts **h h'**.

The tension of the spring is regulated, according to the required pressure of steam, by setting up the jam-nuts **h h'**, and when set the valve is fastened to the inside of the boiler, secure against any interference with it by the engineer or other parties.

When the steam rises above the degree of pressure allowed, it forces up the valve by the contraction of the spring **c** and escapes, thus affording a compact, durable, and reliable safety-valve.

Having described the construction and operation of my invention, what I claim as new, and desire to secure by Letters Patent, is—

1. The capsular spring **c**, combined with the valve **B**, the valve-stem **d**, and the jam-nuts **h h'**, constructed and arranged as and for the purposes herein described.

2. The flange **A** and stand **b**, combined with the valve **B**, and the capsular spring **c**, constructed and arranged as and for the purposes herein specified.

HORATIO ANDERSON.
